STAIR RAIL BRACKET HANGER

Claude H. Cousins, Kansas City, Mo.

Application April 7, 1942, Serial No. 438,033

4 Claims. (Cl. 20—10)

This invention relates to new and useful improvements in means for supporting stair hand rails.

The principal object of the present invention is to provide a bracket and hanger adapted for removably supporting stair hand rails.

Another important object of the invention is to provide a hanger and bracket for stair rails which can be installed conveniently in old buildings as well as new.

Other important objects and advantages of the invention will become apparent to the reader of the following description.

In the drawings:

Figure 1 represents a side elevational view showing the hanger installed on a side of a stud, the latter, laths, and plaster being shown in dashed lines.

Figure 2 is an edge elevational view of the hanger.

Figure 3 is a top plan view of the hanger.

Figure 4 is a closure button for closing the upper end of the hanger when not in use.

Figure 5 is a face elevational view of the closure button.

Figure 6 is a side elevational view of a modified form of hanger especially adapted for installation in old houses.

Figure 7 is a front elevational view of the hanger shown in Figure 6.

Figure 8 is a side elevational view of the bracket.

Figure 9 is a section on the line 9—9 of Figure 8.

Figure 10 is a plan view of the bracket.

Figure 11 is a fragmentary vertical sectional view of a wall showing the present invention in side elevation.

Referring to the drawings wherein like numerals designate like parts, it can be seen in Figure 1, that numeral 5 denotes a stud through which the hanger unit of the present invention is attached, this unit being generally referred to by numeral 6.

In Figure 1, numeral 7 denotes laths attached to the stud 5 and over this plaster. The unit 6 comprises a substantially square metal plate 9 having openings 10 in the corner portions thereof for the reception of securing means which are driven into the stud 5.

The upper outer corner of the plate 9 is provided with a protuberance 11 which is intended to extend through the laths 7 and terminate flush with the outer side of the plaster 8.

Numeral 12 denotes an inclined barrel which

is disposed substantially diagonally across approximately one-half of the plate 9 and terminates with an oblique upper end flush with the outer edge of the protuberance 11, to the end that this barrel 12 will also terminate flush with the outside of the plaster 8.

The underside of the barrel 12 adjacent the upper end thereof has a horizontally formed and threaded opening 13 therein for the reception of a set screw 14.

It can be seen in Figures 6 and 7 that this unit is somewhat modified.

The modified unit is generally referred to by reference character 6a and comprises a plate 9a provided with a vertically disposed attaching flange 15 at the outer edge portion thereof, this flange 15 being formed with openings 16a through which securing elements can be disposed.

This latter form of the invention is used where installation is required on old buildings where it would be difficult to get to the side of a stud 5. An opening just large enough to insert the device in sideways and place the flange 15 against the stud 5 is required as the flange 15 is secured against the outer edge of the stud.

In this latter form of hanger, the barrel 12a and securing means 14a are the same as in the form of the invention shown in Figure 1.

In the event a hand rail is not to be employed after installation of the hanger, a closure button 16, ornate on the outside if desired, is affixed to the exposed upper end of the barrel 12 or the barrel 12a through the medium of spring fingers 17 which can be disposed into the barrel.

Figure 8 shows a hanger, several of which may be employed with a hand rail.

This hanger comprises a bar including a straight portion 18 for disposition into the barrel 12 or the barrel 12a. From the straight portion 18 extends a horizontal portion 19 and from there a stepped up portion 20 to another horizontal portion 21. On this horizontal portion 21 is a U-shaped clamp 22 having aperatured ears 23 which are bolted or screw fastened to the bottom side of a stair rail (not shown).

While the foregoing specification sets forth the invention in specific terms, it is to be understood that numerous changes in the shape, size and materials may be resorted to without departing from the spirit and scope of the invention as claimed hereinafter.

Having described the invention, what I claim as new is:

1. In combination with a wall structure, a

socket secured to one side of a studding and projecting to a point substantially flush with the outside of the wall, an arm having one end detachably disposed in the socket and provided at its outer end with a hanger, and a stair rail secured to the hanger.

2. In combination with a wall structure including a studding, a plate attached to the studding and provided with a socket structure thereon protruding to a point flush with the outside of the wall structure, an arm having one end disposed in the socket structure and provided with stair rail attaching means at the outer end thereof.

3. In combination with a wall structure including a studding, a plate attached to the studding and provided with a socket structure thereon protruding to a point flush with the outside

of the wall structure, an arm having one end disposed in the socket structure and provided with stair rail attaching means at the outer end thereof, said socket structure being inclinedly disposed on the plate, said arm having a horizontally disposed portion at its outer end.

4. In combination with a wall structure including a studding, a plate attached to the studding and provided with a socket structure thereon protruding to a point flush with the outside of the wall structure, an arm having one end disposed in the socket structure and provided with stair rail attaching means at the outer end thereof, said plate having a portion extending to terminate flush with the outer side of the wall, said socket structure being disposed over a portion of the plate and said extension.

CLAUDE H. COUSINS.
